UNITED STATES PATENT OFFICE.

CATHARINE F. CORCORAN, OF WILLISTON, NORTH DAKOTA.

ARM-BAND.

1,164,928.

Specification of Letters Patent. Patented Dec. 21, 1915.

Application filed June 12, 1915. Serial No. 33,816.

To all whom it may concern:

Be it known that I, CATHARINE F. CORCORAN, a citizen of the United States, residing at Williston, in the county of Williams 5 and State of North Dakota, have invented certain new and useful Improvements in Arm-Bands, of which the following is a specification, reference being had to the accompanying drawings.

10 My present invention relates particularly to new and useful improvements in supports or hangers for a conductor wire for gas tubes of electric and gas irons and has especial reference to a device of this character which is adapted for attachment to the operator's arm.

15 The principal object of the invention is to provide a supporter or hanger of the character specified which is formed in the nature of an arm band adapted to be worn on the arm of the person using the iron and to be employed as a means for taking up the slack in the conducting wire or gas tube, so that there will be no hampering length 20 of wire or tubing to annoy and inconvenience the operator when the iron is being used.

25 A more specific object of the invention is to provide an arm band of the character specified which is so designed that it may be quickly and easily applied to or removed from the operator's arm and may be easily engaged with or disengaged from the cord or tubing.

30 The above, and other incidental objects of a similar nature, which will be hereinafter more specifically treated are accomplished by such means as are illustrated in the accompanying drawings, described in the following specification, and then more particularly pointed out in the claim which is appended hereto and forms part of this application.

35 With reference to the drawings, wherein there has been illustrated the preferred embodiment of this invention, as it is reduced to practice, and throughout the several views of which similar reference numerals designate corresponding parts,

40 Figure 1 is a perspective view showing the arm-band in use on an operator's arm and illustrating the manner in which the device is adapted to take care of the slack in the conductor wire or tubing; Fig. 2 is 45 an enlarged perspective view, showing the device in detail.

In taking up the detailed description of the invention, reference will first be had particularly to Fig. 1, wherein the device is illustrated in use. As shown in this 60 figure, the hanger or support consists in an elastic arm band 10, which is applied to the arm of the person using the iron indicated at A, and is accompanied by a hanger loop 11, which receives the conductor wire, indicated at B. As will be readily discerned, upon reference to Fig. 1, the conductor wire may be engaged with the supporting loop 11, in such manner that this member will 65 act to take up the slack which might otherwise occur in the portion of the conductor wire adjacent to the iron. A slack in the conductor wire will, of course, be present as indicated at 12, but, as illustrated in Fig. 1, the slack will be so located as not to interfere with the convenient handling of the 70 iron. Obviously, therefore, the present device constitutes a means for eliminating one of the principal objections entered against 75 irons of the electric and gas types.

80 As regards the specific construction or formation of the device, it is to be primarily noted that it may be subjected to numerous modifications, without departing in any way from the spirit of the invention. However, 85 the preferred embodiment of the device includes the arm band 10, which is formed from a strip of elastic cloth of the well-known type. One end of this cloth is provided with an adjusting buckle 13, which 90 is preferably of the kind employed in connection with garters and suspenders. The member 13 is, of course, adapted to permit the arm band to be lengthened or shortened at will, to fit it to arms of different sizes. 95 The loop 11, preferably consists in a strip of leather, the one end of which is provided with a conventional connecting member 14, which serves to attach the strap to the arm band. The other end of the strap is provided with a socket 15, of the snap type, which is adapted to engage with the stud 16 secured to the strap immediately adjacent to the end thereof which is connected to the member 15. As will be readily observed, 100 the loop may be opened and passed around the conductor wire or tubing and then closed by engaging the socket over the stud member.

105 Particular attention is directed to the fact that the present device prevents the occurrence of slack in the conductor wire or

tubing at that point whereat the presence of slack would most greatly inconvenience and hamper the use of the iron but it does not reduce the effective length of the conductor wire or tubing.

In reduction to practice, it has been found that the form of this invention illustrated in the drawings and referred to in the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the ad-

vantages of this invention, as defined by the appended claim.

What is claimed is:—

The combination with an iron and the flexible energy supplying member therefor, of a supporting loop having a snap fastener connecting its terminals, an elastic arm band for attaching the loop to the arm of the person using the iron, and an adjusting buckle for the arm band.

In testimony whereof I hereunto affix my signature in the presence of two witnesses.

CATHARINE F. CORCORAN.

Witnesses:

W. H. SHEMORRY,
A. M. PIKE.
